UNITED STATES PATENT OFFICE.

SIGMUND ASHNER, OF NEW YORK, N. Y.

BATHING-GARMENT.

SPECIFICATION forming part of Letters Patent No. 313,845, dated March 17, 1885.

Application filed July 3, 1884. (No model.)

To all whom it may concern:

Be it known that I, SIGMUND ASHNER, of the city of New York, in the county and State of New York, have invented a new and Improved Bathing-Garment, of which the following specification is a full, clear, and exact description.

This invention relates to a new bathing-suit which may be inflated while the bather is in the water. The suit is provided at the back with a pocket, into which a rubber bag is loosely inserted. This bag is connected to a tube, by which it may be inflated, and which may be passed through a ring, all as herein-after more fully set out.

In the accompanying drawings, Figure 1 is a perspective view of my suit in use, showing the bag inflated. Fig. 2 is a detail perspective view of the bag, and Fig. 3 a detail view 20 showing the fastening for the pocket.

The letter A represents a bathing-garment of any suitable design. Upon the back of this garment there is formed a pocket, a, by sewing to the garment a piece of flannel or other fabric. This fabric I prefer to attach permanently on three of its sides, while the fourth side may be fastened by hooks and eyes b, as indicated in Fig. 3.

Within the pocket a there is loosely placed 30 a rubber bag, d, having a tube, e, that projects through a small opening in the pocket a. This bag d is not attached at any of its edges, but is entirely disconnected from garment and pocket. To this feature I attach considerable

importance, because the inflation of the bag 35 will not strain the garment. The bag may be readily inserted and removed by opening fastenings b, if the garment is to be washed.

f is a ring attached by a string to the breast of the garment and within easy reach of the 40 wearer. Through this ring the tube e is passed when the bag is empty. If the bag is to be inflated, the tube is withdrawn from the ring, the bag is blown up, and then the tube is doubled up and again passed through the 45 ring. This will effectively prevent the escape of air from the bag. Fig. 1 shows the garment with the tube in this position.

My bathing-suit is intended to be worn with the bag empty under ordinary circumstances. 50 In case of emergency, however, the bather can in a very little time inflate the bag. Thus if he should become fatigued or meet dangerous currents, he may readily convert his suit into a life-preserver. The position of the bag 55 is such that it will properly hold the head and shoulders of the wearer above the water. The suit may also be worn with advantage by pupils learning to swim.

I claim as my invention—
The combination of garment A with pocket a, bag d, tube e, and ring f, substantially as specified.

SIGMUND ASHNER.
